UNITED STATES PATENT OFFICE

2,059,014

STARTING MEANS FOR VAPOR ELECTRIC APPARATUS

Lysle W. Morton, Schenectady, N. Y., assignor to General Electric Company, a corporation of New York

Application November 8, 1932, Serial No. 641,738

13 Claims. (Cl. 175—354)

My invention relates to means for and methods of starting vapor electric apparatus, particularly of the mercury vapor type such as the mercury arc rectifier, and has for its principal object the provision of an improved excitation anode arrangement and method of operation whereby the pick-up of the arc by the main or power anodes is facilitated.

It is common practice in the operation of vapor electric devices of the mercury arc type to accomplish the starting of the device by striking an arc between the cathode and an ignition electrode to form a cathode spot on the mercury, then establishing a discharge current between the cathode and excitation anodes, and finally establishing the power current between the cathode and the main anodes. One purpose of establishing the discharge current between the excitation anodes and the cathode is to provide ionization for the main anodes to facilitate the pick-up of the arc by the latter anodes.

Certain types of such mercury arc devices, particularly rectifiers or the like having in general excellent operational characteristics have been designed for large power and high voltage. To assist in preventing the occurrence of arc-back in the above mentioned mercury arc devices intended for large power and high voltage operation it has been found desirable to provide a high degree of baffling, i. e., the provision of highly efficient baffle elements such as anode shields, baffle members proper in the arc path within the shields, grid members mounted adjacent the anodes and functioning in part as baffles, and other suitable baffle elements associated with the anodes or mounted in the arc path, or both. This provision of extremely efficient baffling has contributed largely to the high rating and voltage of the mercury arc device by thus assisting in the prevention of arc-back between cathode and main anodes or elsewhere.

Difficulties have however been encountered in certain instances in the operation of mercury arc devices, particularly of the large power and high voltage type above described provided with a high degree of baffling, due to hard starting or pick-up of the arc by the main or power anodes, this hard pick-up being attributable in part at least to the presence of the baffling which as above noted contributes to the high power and voltage rating of the device.

I have found that the hard starting, or hard pick-up of the arc by the main anodes encountered at times in certain types of vapor electric devices, for example of the high power mercury

arc type above described, is due in great measure to the fact that, in spite of the provision of excitation means hitherto employed such as an excitation anode or anodes mounted within the evacuated receptacle of the device, the arrangement and method of operation of the excitation means were such that the correct ionization conditions, necessary to insure pick-up of the arc by the main anodes, were not present in the arc path and in the region of the main anodes during the period immediately preceding and including the instant at which the main anodes should pick up the arc.

In accordance with my invention the above starting difficulties are overcome, and the advantages inherent in a high degree of baffling may be retained, by the provision of excitation means preferably comprising a plurality of excitation anodes so mounted with reference to the main anodes and so energized from a suitable current source that at the firing or pick-up periods of the main anodes or immediately before these firing periods, the ionization conditions in the main anode regions and in the arc path are such that easy pick-up of the arc by the main anodes is insured without danger of the occurrence of arc-back.

In carrying my invention into effect I provide a plurality of excitation anodes each associated with a different one of the main or power anodes or with a different group of the main anodes and each mounted in such a predetermined position, with reference to the main anode group with which it is associated, in the region of this associated main anode or group, that the ionization provided by each excitation anode to its corresponding main anode or group of main anodes comes into relatively close juxtaposition thereto.

The excitation anodes are energized preferably though not necessarily from an alternating current source. In order to insure that the ionization supplied by each excitation anode to its associated main anode or group thereof, when the excitation anodes are energized from an alternating current source, shall be supplied at such time that the ionization will assist to the fullest extent the corresponding main anode or group in picking up the arc, means are provided to energize the excitation anodes in the same sequence as that of the firing or arc pick-up periods of the corresponding main anodes or groups thereof. To this end potentials from a suitable source, as a transformer supplied from the same alternating current source as that from which potentials are impressed upon the main anodes,

may be impressed upon the excitation anodes to cause the positive half-waves of the potential supplied to each of the excitation anodes to occur at substantially the same period as that of the positive half-waves of the potential supplied to the corresponding main anode or group of main anodes, the firing or discharge periods of the excitation anodes thus substantially synchronizing with the firing or arc pick-up periods of the main anodes or groups.

I have found, however, that instead of substantially synchronizing the firing periods of the excitation anodes and their corresponding main anodes or groups, it may be necessary or desirable in certain instances to operate the excitation anodes with potentials shifted to a certain degree with respect to the phase of the potentials impressed upon the corresponding anodes or groups. In accordance with my invention means are, therefore, preferably provided to shift the phase of the excitation anode potentials either leading or lagging with respect to the potentials impressed upon the corresponding main anodes or groups.

My invention will be better understood from the following description when considered in connection with the accompanying drawings and its scope will be pointed out in the appended claims.

Referring to the drawings, Fig. 1 is a diagrammatic representation of a vapor electric apparatus, including a mercury arc device, in which my invention has been embodied; Fig. 2 is a cross sectional view of the mercury arc device included in Fig. 1, this view illustrating the mounting of elements, as cathode, main anodes, excitation anodes and baffle elements, included in this device; and Figs. 3 to 8 are diagrammatic representations of vapor electric apparatus embodying modifications of my invention.

In Fig. 1 my invention is illustrated as embodied in an electric apparatus including an alternating current circuit 10 and a direct current circuit 11 between which power may be transferred by means of a vapor electric apparatus such as a mercury arc device 12 which is connected to the alternating current circuit 10 through a transformer apparatus 13. For purposes of illustration the device 12 is shown as a 12-phase mercury arc rectifier having a cathode 14, twelve main or power anodes 15 . . . 26 adapted to fire or pick up the arc in sequence in the order indicated by the numerals denominating these anodes, the rotation of the firing or arc pick-up being assumed to be clockwise in the example shown in Fig. 1. To form the cathode spot on the surface of the mercury cathode 14, a usual ignition anode apparatus including an ignition anode 27, operating solenoid 28 and spring 29 may be provided.

As illustrated in Fig. 2, the main anodes, only one of which is shown in this figure denominated by the numeral 30, may be enclosed within an anode shield 31 extending downwardly within the evacuated receptacle 32 and having a baffle 33 and a grid 34 mounted in the arc path within the shield, the members 32, 33 and 34 all functioning in part at least as baffle elements in the arc paths between the main anodes, as 30, and the cathode 14.

In the embodiment of my invention illustrated diagrammatically in Fig. 1 and in certain details in Fig. 2 the excitation means in accord-

ance with the invention comprises six excitation anodes 35 . . . 40 each associated with a different group of two each of the main anodes 15 . . . 26, each of the excitation anodes 35 . . . 40 being mounted between the two main anodes constituting the corresponding group thereof. As will be evident from an inspection of Fig. 1 and of the cross sectional view of Fig. 2, the excitation anodes, only one of which is shown in Fig. 2 denominated by the numeral 41, are mounted in the regions of the main anodes, each excitation anode being closely adjacent the anode shield members of the corresponding pair of main anodes and relatively high up in the evacuated receptacle 32, for example preferably at least as high above the cathode as the main anodes.

To energize the excitation anodes 35 . . . 40 each of the latter is preferably connected through a suitable reactor 42 to a different phase of a 6-phase alternating current source, for example to the different secondary phases 43 . . . 48 of an auxiliary transformer 49 the primary 50 of which may be connected to the alternating current circuit 10.

The connections of auxiliary transformer 49 are assumed to be so arranged that the six excitation anodes 35 . . . 40 fire or carry current in sequence in the order indicated by the numerals denominating these anodes, the rotation 30 of the firing, therefore, being clockwise as in the case of the firing of the main anodes 15 . . . 26. Further, the connections of main transformer 13 and auxiliary transformer 49 are assumed to be such that the positive half-waves of the potentials impressed upon each of the excitation anodes, firing in the sequence 35 . . . 40, occur during the positive half-waves of the potentials impressed upon the corresponding groups of main anodes, firing in the sequence 15, 16 . . . 25, 26. 40

The current-carrying periods of the excitation anodes 35 . . . 40 may be substantially synchronized with those of the corresponding groups 15, 16 . . . 25, 26 of the main anodes. Preferably, however, a suitable phase-shifting means, 45 such as a phase shifter connected between the auxiliary transformer 49 and alternating current circuit 10, may be provided to cause the phase of the potentials impressed upon the excitation anodes 35 . . . 40 to be shifted either leading or lagging with respect to the potentials impressed upon the corresponding groups 15, 16 . . . 25, 26 of the main anodes.

The operation of my invention will be clearly understood from the drawings and from the foregoing description of one embodiment thereof. In operation, potentials from main transformer 13 and auxiliary transformer 49 are impressed upon the main anodes 15 . . . 26 and the excitation anodes 35 . . . 40 respectively, and at the same time the cathode spot is formed upon the cathode 14 by operation of the ignition apparatus 27, 28, 29 in the usual manner.

The potentials from transformer 13, existing upon the main anodes 15 . . . 26 at the same time that the cathode spot is formed, tend to cause these anodes to fire, or pick up the arc in sequence. Heretofore a certain degree of ionization tending to assist in the pick-up of the arc by the main anodes has been supplied to these anodes from excitation or holding anodes the principal purpose of which was to maintain an arc in the device at low loads when the arc at the main anodes tended to fail. But in many 75

instances the pick-up of the arc, thus incidentally assisted by the action of holding anodes designed primarily for another purpose, has been difficult or even impossible, due, for example in 5 the large power high voltage mercury arc devices hereinbefore mentioned, to the presence of baffle elements, such as the anode shields 31, the baffle members 33 and the grids 34, associated with the main anodes or in the arc path 10 between these anodes and the cathode 14.

In the operation of the excitation means in accordance with my invention the pick-up of the arc by the main anodes 15 . . . 26 is, however, made easy and certain by the action of the excitation anodes 35 . . . 40 each associated in the 15 example shown, with a different group constituted by two of the main anodes.

It will be noted that each excitation anode is mounted relatively high up in the receptacle 12, 20 each in the region of its corresponding group of main anodes and closely adjacent to this corresponding group. Ionization from the excitation anodes, when these anodes carry current due to potentials from auxiliary transformer 49 impressed thereupon, will therefore be supplied to the regions of each of the groups of main anodes 15, 16 to 25, 26 in close juxtaposition to these anodes.

To make certain that just sufficient ionization 30 is supplied to each group of main anodes to overcome hard pick-up of the arc without causing arc-back due to too great a degree of ionization in the receptacle 12, in accordance with my invention the potentials supplied by auxiliary 35 transformer 49 are impressed upon the excitation anodes 35 . . . 40 in the same sequence as that of the potentials impressed by main transformer 13 upon the groups of main anodes 15, 16 . . . 25, 26 and in such a manner that 40 the ionization supplied to each group from its corresponding excitation anode occurs either substantially synchronously with the firing period of the group, or lagging or leading this firing period by a number of degrees determined by the 45 phase shifting means. Preferably, in usual cases the phase of the potentials impressed upon the excitation anodes should be slightly leading with respect to the firing periods of the main anode groups in order that ionization may be present, 50 in any given group region, immediately preceding the firing period of the group.

My invention has been described and illustrated in connection with a vapor electric device including one excitation anode for a group of 55 main anodes, the groups in the present example being constituted each by two main anodes. It will be clearly understood, however, that the starting arrangement in accordance with my invention may include other numbers of excitation anodes relative to the number of main anodes. For example, the number of excitation anodes may be the same as that of the main anodes as illustrated in Fig. 3, wherein the numerals 51 and 52 designate the main and excitation anodes respectively. Or the number of excitation anodes may be the same as the number of groups of main anodes, the constituent main anodes of the groups being arranged, however, for parallel operation, as illustrated in Fig. 4, wherein the 70 numerals 54 and 54' designate pairs of main anodes arranged for parallel operation and the numerals 55 designate the excitation anodes. Further, each excitation anode may be associated with a group constituted by more than two main anodes as illustrated in Fig. 5. For example, in

5 a vapor electric device provided with twenty-four main anodes designated by the numerals 56, six excitation anodes designated by the numerals 57, or one for each group of four main anodes may be sufficient.

It will be understood, further, that while the plurality of excitation anodes have been described as so disposed that each is in the same position with reference to the main anodes, the excitation anodes may be variously arranged. 10 For example, certain of the excitation anodes may be at one level within the evacuated container and others at a different level as illustrated in Figs. 6 and 7 which are plan and cross-sectional views respectively of a rectifier in which the invention 15 is embodied. The numerals 58 designate the main anodes and numerals 59 and 60 represent two sets of excitation anodes mounted at different levels with respect to the main anodes.

It will also be understood that in certain cases 20 the set of excitation anodes furnishing the ionization for the main anodes are necessarily placed in such a position that these excitation anodes themselves require to be assisted in starting, or picking up their excitation arc from the cathode, 25 by ionization supplied to them from a second set of excitation anodes mounted closer to the cathode. Thus in the modification shown in Fig. 8, wherein the numerals 61 designate the main anodes, one set of excitation anodes designated by 30 the numerals 62 may be mounted as in the embodiment of the invention shown in Fig. 1 and a second set of excitation anodes designated by the numeral 63 may be mounted nearer the cathode. In this case, in igniting the set of excitation 35 anodes associated directly with the main anodes and which are necessary in order to obtain successful starting of these main anodes, the ionization must migrate from one set of excitation anodes to another set, or other sets in sequence, 40 and finally to the main anodes.

What I claim as new and desire to secure by Letters Patent in the United States is:

1. The combination with a polyphase vapor electric apparatus including a liquid cathode, 45 means to form a cathode spot thereon, a plurality of main anodes arranged to carry current in a predetermined sequence, and a plurality of anode shields having baffle members mounted therein, said shields and baffle members being so 50 arranged with reference to the corresponding main anodes as to tend to prevent pick-up of the arc by said main anodes, of a plurality of excitation anodes arranged to carry current to said cathode spot in the same sequence as that of the 55 main anodes, said excitation anodes being respectively adjacent to the corresponding main anodes and arranged to supply ionization therefor to facilitate picking up of the arc thereby.

2. The combination with a polyphase vapor 60 electric apparatus including a liquid cathode, means to form a cathode spot thereon, a plurality of groups of main anodes arranged to carry current in a predetermined sequence, and a plurality of anode shields having baffle members 65 mounted therein, said shields and baffle members tending to prevent pick-up of the arc by said main anodes, of a plurality of excitation anodes arranged to carry current to said cathode spot in the same sequence as that of said groups of 70 main anodes, each of said excitation anodes being mounted adjacent a different one of said groups to supply ionization to the main anodes constituting the corresponding one of said groups to facilitate picking up of the arc thereby. 75

3. In combination, a polyphase vapor electric apparatus including a liquid cathode, means to form a cathode spot thereon, a plurality of main anodes, and a plurality of anode shields having baffle members mounted therein, said shields and baffle members tending to prevent pick-up of the arc by said main anodes, means to impress potentials upon said main anodes in sequence, a plurality of excitation anodes mounted respectively adjacent to the corresponding main anodes, and means to impress in sequence upon said excitation anodes potentials sufficient to cause discharge current to flow between said excitation anodes and said cathode spot, said potentials being substantially synchronized with the corresponding main anode potentials whereby ionization is supplied to the main anodes in sequence from the corresponding excitation anodes for facilitating the picking up of the arc by said main anodes.

4. In combination, a polyphase vapor electric apparatus including a liquid cathode, means to form a cathode spot on said cathode, a plurality of main anodes, and a plurality of anode shields having baffle members mounted therein, said shields and baffle members tending to prevent pick-up of the arc by said main anodes, means to impress potentials upon said main anodes in sequence, a plurality of excitation anodes mounted respectively adjacent to the corresponding main anodes, means to impress upon the excitation anodes potentials sufficient to initiate current flow from said excitation anodes to said cathode spot and in a sequence corresponding to that of the potentials impressed upon the main anodes, whereby ionization is supplied to the main anodes in sequence from the corresponding excitation anodes for facilitating the picking up of the arc by the main anodes, and means to determine the phase of the excitation anode potentials with relation to the phase of the corresponding main anode potentials.

5. In combination, a polyphase vapor electric apparatus including a mercury cathode, means to form a cathode spot on said cathode and a plurality of main anodes, means to impress in sequence upon said main anodes potentials tending to cause pick-up of the arc between cathode and anodes, means in said apparatus tending to prevent said pick-up comprising a plurality of anode shields having baffle members mounted therein, a plurality of excitation anodes adjacent respectively to the corresponding main anodes, and means to impress potentials upon said excitation anodes sufficient to initiate current flow from said excitation anodes to said cathode spot whereby ionization is supplied to each of said main anodes, said ionization being of such amount and said excitation anodes each being so disposed with reference to the region in said apparatus of the corresponding main anode that the tendency of said second-named means to prevent said pick-up is overcome without said ionization being sufficient to cause arc back in said apparatus.

6. In combination, a vapor electric apparatus including a cathode, a plurality of groups of main anodes and means to impress thereon in sequence potentials tending to cause pick-up of the arc between cathode and anodes, means in said apparatus tending to prevent said pick-up, a plurality of excitation anodes each associated with a different one of said groups of main anodes, and means to impress potentials upon said excitation anodes to supply ionization to each of said groups, said ionization being of such amount and each of

said excitation anodes being so disposed with reference to the region in said apparatus of the corresponding group of main anodes that the tendency of said second-named means to prevent said pick-up is overcome without said ionization being sufficient to cause arc back in said apparatus.

7. In a polyphase vapor electric apparatus including a mercury cathode, means to form a cathode spot on said cathode, a plurality of main anodes and means to impress thereon alternating potentials to cause said main anodes to pick up the arc in said apparatus in a predetermined sequence, a plurality of anode shields having baffle members mounted therein, said shields and baffle members tending to prevent said pick-up, and a plurality of excitation anodes, the method of facilitating the pick-up of the arc by the main anodes which includes impressing upon the excitation anodes alternating potentials sufficient to initiate discharges between said excitation anodes and said cathode spot and in the same sequence as that of the corresponding main anode potentials, and supplying ionization from each of the excitation anodes to at least one of the corresponding main anodes.

8. In a polyphase vapor electric apparatus including a mercury cathode, means to form a cathode spot on said cathode, a plurality of main anodes and means to impress upon said anodes in sequence alternating potentials tending to cause said main anodes to pick up the arc in said apparatus, means in said apparatus tending to prevent said pick-up of the arc, comprising a plurality of anode shields having baffle members mounted therein and a plurality of excitation anodes adjacent respectively to the corresponding main anodes, the method of operation which includes impressing potentials upon the excitation anodes sufficient to initiate discharges between said excitation anodes and said cathode spot, thereby to supply to each of the main anodes sufficient ionization to overcome the tendency of said last-named means to prevent pick-up of the arc by the main anodes, said ionization being at the same time insufficient to cause arc back in the apparatus.

9. In a polyphase vapor electric apparatus including a mercury cathode, means to form a cathode spot on said cathode, a plurality of main anodes and means to impress upon said anodes in sequence alternating potentials tending to cause said main anodes to pick up the arc in said apparatus, means in said apparatus tending to prevent said pick-up of the arc, a plurality of anode shields having baffle members mounted therein, said shields and baffle members tending to prevent said pick-up, and a plurality of excitation anodes adjacent respectively to the corresponding main anodes, the method of operation which includes initiating discharges between said excitation anodes and said cathode spot to supply from the excitation anodes to the main anodes ionization in such amount and so disposed with reference to the regions of the main anodes that said tendency of the said second-named means to prevent pick-up of the arc by the main anodes is overcome, said ionization being insufficient to cause arc back in the apparatus.

10. In a vapor electric apparatus including a mercury cathode, means to form a cathode spot on said cathode, a plurality of main anodes, means to impress thereon alternating potentials to cause said main anodes to pick up the arc in

- said apparatus in a predetermined sequence, and a plurality of excitation anodes, the method of operation which includes impressing upon the excitation anodes alternating potentials sufficient 5 to initiate discharges between said excitation anodes and said cathode spot, said excitation anode potentials being in the same sequence as that of the corresponding main anode potentials, and determining the phase of the excitation anode potentials with relation to the corresponding main anode potentials.
11. In a polyphase vapor electric apparatus including a mercury cathode, means to form a cathode spot on said cathode, a plurality of main anodes, means to impress thereon alternating potentials to cause said main anodes to fire in a predetermined sequence, a plurality of anode shields having baffle members mounted therein, said shields and baffle members tending to prevent said pick-up, and a plurality of excitation anodes, the method of operation which includes impressing upon the excitation anodes alternating potentials sufficient to initiate discharges between said excitation anodes and said cathode spot, said excitation anode potentials being in the same sequence as that of the corresponding main anode potentials, and causing the phase of said excitation anode potentials to be leading 25 with respect to the firing periods of the corresponding main anodes.
12. The combination, with a polyphase vapor electric apparatus, including an evacuated receptacle having mounted therein a mercury cathode, 30 a plurality of main anodes arranged to carry current in a predetermined sequence, and a plurality of anode shields having baffle members
- mounted therein, said shields and baffle members tending to prevent pick-up of the arc by said main anodes, of a plurality of excitation anodes arranged to carry current in the same sequence as that of the main anodes, said excitation anodes being respectively adjacent to the corresponding main anodes and arranged to supply ionization therefor to facilitate picking up of the arc thereby, certain of said excitation anodes being mounted in said receptacle at one level 10 with respect to said main anodes and others of said excitation anodes being mounted at a different level with respect to said main anodes.
13. The combination, with a polyphase vapor electric apparatus, including a mercury cathode, 15 a plurality of main anodes arranged to carry current in a predetermined sequence, and a plurality of anode shields having baffle members mounted therein, said shields and baffle members tending to prevent pick-up of the arc by said main anodes, of a plurality of excitation anodes respectively adjacent to the corresponding main anodes and arranged to carry current in the same sequence as that of the main anodes, and 20 a second plurality of excitation anodes mounted closer than said first-named excitation anodes to said cathode, said second plurality of excitation anodes being arranged to supply ionization to said first-named plurality of excitation anodes 25 to facilitate picking up of the arc by said first-named excitation anodes, said first-named excitation anodes being arranged to supply ionization to said main anodes to facilitate picking up of the arc by said main anodes.
